UNITED STATES PATENT OFFICE.

ANTHONY LEON AND JAMES LATTIMER, OF WORCESTER, MASSACHUSETTS.

ICE-CREAM-CONE STORING AND DISPENSING DEVICE.

Application filed June 21, 1926. Serial No. 117,240.

This invention relates to a device for storing ice-cream cones and the like and for removing them therefrom.

The principal objects of the invention are 5 to provide a storing device which will keep the ice-cream cones away from dust and other contamination, and which will store them in piles in such a way that they can be brought around into position for discharge 10 at the bottom; to provide means for discharging them, and means for preventing more than one being discharged at a time; to provide various improvements in the discharging means to make it effective to always 15 work and work properly; to provide an improved means for holding the cones back so that after one is discharged the rest of the pile will be retained in the casing; and to provide a device for lowering the cones 20 into the casing without injuring them.

Other objects and advantages of the invention will appear hereinafter.

Reference is to be had to the accompanying 25 drawings, in which

Fig. 1 is a side view of a cone dispenser constructed in accordance with this invention;

Fig. 2 is a plan of the same;

Fig. 3 is a side view showing the use of a 30 tool for lowering a pile of cones into the device;

Fig. 4 is a plan of the holding means therefor partly in section on the line 4—4 35 of Fig. 3;

Fig. 5 is a view similar to Fig. 3 of the lowering device on enlarged scale showing it as it appears when being drawn out;

Fig. 6 is a side view of a part of the bottom 40 of the device;

Fig. 7 is a sectional view through the center of Fig. 6 showing a latch for holding the cabinet from turning;

Fig. 8 is a bottom plan view of the cabinet 45 showing the way of holding the ice-cream cone therein;

Fig. 9 is a similar view showing the means for retaining the second cone above when one is dropped out of the cabinet;

Fig. 10 is a view similar to Fig. 8, showing the valve open so that the bottom cone can be dropped out;

Fig. 11 is a view similar to Fig. 9 showing these parts in the position assumed when 55 the other parts are in the position shown in Fig. 10; and

Fig. 12 is a side view with the bottom of the cabinet in section on the line 12—12 of Fig. 10.

This invention is designed for the purpose 60 of storing ice-cream cones and keeping them in a clean and sanitary condition, but, of course, is capable of use for other similar purposes. It is shown as being built with a stationary base 10, preferably of sheet metal, 65 supporting a stationary bottom plate 11 of polygonal shape. Supported in the base is a central vertical hollow shaft 12 which extends clear to the top. Mounted to turn on this shaft is a cabinet 13. The cabinet has 70 a central vertical tube 14 extending throughout its length vertically for receiving the shaft, and to which are affixed partitions or walls 15 radiating from the center and secured to the side faces 16 of the cabinet. 75 These side faces are formed of sheet metal at the top and along their edges, but preferably with glass or other transparent material in the form of panels 17 extending from the top to the bottom thereof. These transparent panels permit the contents to be seen and allow the operator to know 80 which of the compartments formed by the walls 15 contain any cones.

For the purpose of holding the cabinet 85 in any position in which it may be placed, it is provided with a series of vertical slots 18 at the bottom, one at each corner, and the stationary bottom 11 is provided with a spring 19 having a latch 20 thereon adapted 90 to enter any of these slots to hold the cabinet from turning. The spring is adapted to be depressed as shown in dotted lines in Fig. 7 for the purpose of permitting the cabinet 95 to be turned when desired. When held in position in one of the slots there will be one of the compartments in the cabinet that will register with the dispensing apparatus.

The stationary bottom 11 is provided with 100 a single opening 21 therethrough, which, as above stated, is located to register centrally with one of the compartments when the latch 20 is in one of the notches 18. This opening 21 is large enough to allow a cone to drop out through it. It is provided with a shutter 22 arranged to close partially. It consists, as shown, of a half dozen levers having arcuate edges pivoted on studs 23 which are adapted to move in radial slots 24 in a ring 25 fastened to the bottom 11 of the cabinet by screws 26. There is an arm 27 projecting from one of the shutter ele-

ments 22 which, when moved as shown in Figs. 8 and 10, will either bring the shutter to the position shown in Fig. 8 in which it prevents the cones from dropping, or into the open position shown in Fig. 10 which permits them to drop.

For the purpose of operating this arm 27 it is provided with a pin 28 and there is a slide 29 which has two slots 30 and 31 which are guided by screws 32 and 33 on the bottom 11. A spring 34 tends at all times to keep this latch in the position shown in Fig. 8, but upon being pushed in against the resistance of the spring 34 a surface 35, which constitutes the edge of a notch in the latch, engages the stud 28 and swings the arm 27 to open the shutter. An adjustable stop screw 36 is shown for engaging the arm 27 and preventing its moving beyond the point shown.

On the latch 29 is a spring 37 which connects this latch with the pin 28 to keep the pin always in contact with the surface 35 until the arm 27 engages the adjusting screw 36. This is shown in Fig. 8, and provides for some lost motion. At the end of the latch plate 29 it is bent at right angles to form an operating end 39. On the bottom 11 is a downwardly extending stationary projection or bracket 40 for the operator to engage with his fore-finger while he operates the latch with his thumb.

From what has been said it will be seen that the operation of this latch will let the cones down. For the purpose of holding up the second cone and allowing only one to be delivered at a time, a holding mechanism is provided. On the latch 29 is an angular slot 41 engaging a pin 42 on a lever 43. In the normal position shown in Fig. 8, this pin is down to the bottom of this slot. When the latch 29 is pushed in, the first effect is to force the pin out of the slot along a flat surface 44 on the latch. This results in swinging the lever 43 from the position shown in Fig. 9 to that shown in Fig. 11. There is a companion lever 45 geared to the lever 43, so that they will swing oppositely, and two arms 46 which constitute a lazy-tongs structure. These arms 46 are pivoted to the levers 43 and 45 by pins 47, working in a single slot 48 in the bottom 11. These pins are mounted on the levers 43 and 45 and connected with the arms by longitudinal slots. These arms are pivoted at 58 and are provided with elevated arms 49 of curved formation so that they constitute holding levers. In the position shown in Fig. 9 these arms are spread apart and have no effect, but when the latch is pushed in to release the bottom cone the arms move in as shown in Figs. 11 and 12 to catch the second cone and hold it up until the latch is again released.

It will be understood that the cones are

loaded in the cabinet by placing them point downward and one in another in a pile as shown in Figs. 1 and 12. In the compartment which registers with the opening 21 one of these cones projects down below. It is obvious that dropping them in from the top would be apt to injure the cones. Therefore the cabinet is provided with means for loading it. This consists of a tube 50 in the form shown. This has a rod 51 extending through it with a fixed head 52 for operating it in opposition to a spring 53 at the top of the rod. The tube is provided with a flange 54 so that the operator can press the rod down with the thumb by engaging two fingers under the flange. In the normal position when the rod is up, as shown in Fig. 3, its end which is pivoted to a flat plate 55 is, of course, drawn up so that this flat plate which is pivoted on a stud 56 will move into horizontal position, a stop 57 being arranged in a position to limit it. In this condition the pile of ice-cream cones 60 is supported by the plate 55 which is of crescent shape, as indicated in Fig. 4, and is lowered down into one of the compartments. When it reaches the bottom the operator presses on the top 52. This forces the rod 51 down and swings the plate or holder 55 into a vertical position, as shown in Fig. 5, so that the whole thing can be drawn out without disturbing the cones deposited by it. This loading device is intended to be held within a hollow rod 12 when not in use. On the top of the cabinet is a removable cover of the same shape as the cabinet.

It will be seen that with this device a large number of ice-cream cones or the like can be stored out of the way of contamination by dust or the like; that a pile of them, perhaps a dozen in number, can be dispensed one at a time by a very simple operation, and no danger of the whole pile falling, or even of a second one being delivered accidentally. Also when one compartment is empty the cabinet can be turned very easily upon manipulating the catch 19-20, and there will be another supply of the same number ready to be delivered. On account of the design and construction of the cabinet a very large number of cones can be stored in a comparatively small space all ready to be delivered as desired.

On account of the simplicity of the loading device, the cabinet can be supplied with a full set of cones without difficulty and without the expenditure of much time. The device has only a few working parts, and these are comparatively simple in construction.

Although we have illustrated and described only a single form of the invention, we are aware of the fact that modifications can be made therein by any person skilled

in the art without departing from the scope of the invention as expressed in the claims. Therefore we do not wish to be limited to all the details of construction herein shown and described, but what we do claim is:—

1. In a device of the character described, the combination with a base having an opening therethrough and means for supporting a pile of conical objects above the opening in axial alignment therewith, thereby when the first named means is opened the bottom cone will drop down below said stationary base, of a pair of pivoted levers having teeth meshing with each other to cause the levers to operate simultaneously in opposite directions about their pivots, and a second pair of levers connected with the first pair having curved arms for engaging the second cone, both operated either inwardly or outwardly at the same time for preventing all but the bottom cone from falling.

2. In an ice-cream cone dispensing device, the combination with a shutter for holding the bottom one of a pile of ice-cream cones, of a pair of levers geared together to swing oppositely, means for swinging the levers away from each other, and a second pair of levers connected with and operated by the first pair, each having an elevated curved arm thereon in position for engaging the second cone of the pile when the shutter is actuated to allow the first one to drop.

3. In a dispensing device for cones and the like, the combination of a support having an opening therethrough and a shutter for said opening adapted to close partially to hold a cone therein, with a lever connected with the shutter, an operating slide adapted to engage said lever, said operating slide having a slanting slot in the edge thereof, a pin projecting into said slot, and means connected with said pin for holding up the cones above the bottom one, when the slide is actuated to open the shutter.

4. In a dispensing device for ice-cream cones and the like, the combination of a support having a circular opening therethrough and a shutter for said opening adapted to close partially to hold a cone therein projecting below the shutter, with means for

opening the shutter to allow the cone to be discharged, comprising a lever connected with the shutter, an operating slide adapted to engage said lever, said operating slide having a slanting slot in the edge thereof and a surface adjacent to the slot parallel with the direction of motion of the slide, a pin projecting into said slot, and means connected with said pin for holding up the cones above the bottom one, when the slide is actuated to open the shutter.

5. In a dispensing device for cones, and the like, the combination with a supporting plate having an opening through it, a shutter adapted to be partly closed to hold a cone with its point projecting down, said shutter having operating arm, a lever connected with the shutter for opening it entirely to allow the cone to descend, an operating slide, a spring for normally holding the operating slide in operative position, said lever having a pin thereon, and a spring connecting the slide with said pin, said slide having a wall adapted to engage the pin when the slide is pushed in to actuate said arm on the shutter and open it.

6. In a dispensing device for ice-cream cones, and the like, the combination with a supporting plate having a circular opening through it, a shutter adapted to be partly closed to hold a cone with its point projecting down below the shutter, said shutter having an operating arm, a lever connected with the shutter for opening it entirely to allow the cone to descend, an operating slide, a spring for normally holding the operating slide in inoperative position, a guide for guiding the slide, said lever having a pin thereon, a spring connecting the slide with said pin, said slide having a notch, one wall of which is adapted to engage the pin when the slide is pushed into actuate said arm on the shutter and open it, and a finger piece on the bottom of the plate to assist the operator in manipulating the slide.

In testimony whereof we have hereunto affixed our signatures.

ANTHONY LEON.
JAMES LATTIMER.
